UNITED STATES PATENT OFFICE.

ALVA D. JONES, OF PHILADELPHIA, PENNSYLVANIA, ASSIGNOR OF ONE-FOURTH TO
EUGENE S. COCHRAN, OF WASHINGTON, DISTRICT OF COLUMBIA, AND ONE-FOURTH
TO E. HAYWARD FAIRBANKS, OF MERCHANTVILLE, NEW JERSEY.

TELEPHONE-RECEIVER.

1,169,038.

Specification of Letters Patent. Patented Jan. 18, 1916.

Application filed May 7, 1913. Serial No. 766,030.

To all whom it may concern:

Be it known that I, ALVA D. JONES, a citizen of the United States, residing in the city and county of Philadelphia, State of Pennsylvania, have invented a new and useful Telephone-Receiver, of which the following is a specification.

My invention consists of a novel construction of a telephone receiver wherein the parts are constructed and arranged in a novel manner.

It further consists of a novel telephone receiver wherein the diaphragm and armature are mounted in a novel manner.

15 It further consists of a novel apparatus for reproducing vocal, instrumental, mechanical or magnetically created sounds.

It further consists of other novel features of construction, all as will be hereinafter 20 fully set forth.

For the purpose of illustrating my invention, I have shown in the accompanying drawings one form thereof which is at present preferred by me, since the same will 25 be found in practice to give satisfactory and reliable results, although it is to be understood that the various instrumentalities of which my invention consists can be variously arranged and organized and that my invention 30 is not limited to the precise arrangement and organization of these instrumentalities as herein shown and described.

Figure 1 represents a sectional elevation of a telephone receiver, embodying my invention. Fig. 2 represents, on an enlarged scale, a sectional view of parts seen in Fig. 1.

Similar numerals of reference indicate corresponding parts.

Referring to the drawings:—In the embodiment seen in Fig. 1 I have shown my novel sound reproducing mechanism as adapted to be employed as a receiver in the usual manner of a telephone receiver. In this embodiment, 88 designates the receiver or casing, within which is located a magnet 89, to which is connected a block 90 by means of fastening devices 91. 92 designates a plate which is secured with respect to the magnet 89 by means of a fastening device 93. 94 and 95 designate electro-magnets operatively connected with the plate 92. The wires 96 and 97 leading from the electro-magnets 94 and 95 respectively pass through the aperture 98 in the casing 88, and these wires 96 and 97, together with the 55 magnet 89, are embedded in wax 99 of any desired nature or other suitable material which is preferably inserted in a molten state so that when the same hardens the wires 96 and 97 will be held in proper suspension and any injury to their insulation or grounding of the wires will be positively prevented. This filling material 99 also serves to maintain the magnet 89 in its proper position. 100 designates a housing 60 for the electro-magnets, said housing having threaded engagement with the casing 88 and having an internal shoulder 101, against which the plate 92 abuts, it being noted that the material 99 surrounds the inner end of 65 the housing 100. The plate 92 is preferably constructed of brass or other similar material and the ends of the magnet 89 extend through the plate 92. 102 designates an armature between which and the electro-magnets 94 and 95 are located the resilient bumpers 103, it being seen that each magnet is provided with one of such bumpers. These bumpers prevent the armature from 70 sticking to the magnet in case of an overcharge of current. The armature 102 is preferably of steel and permanently magnetized and is insulated from a diaphragm 104, by which it is centrally supported, as will be best understood by reference to Fig. 75 80 2. 105 designates a fastening device, such as a screw, which is insulated from the diaphragm 104 and the armature 102 by a tube 106 of insulating material, an insulating washer 107 being provided and also an insulating washer 108, whereby the armature and diaphragm are positively insulated from each other, as is apparent. 109 designates a nut for the screw 105. The purpose of 85 insulating the armature from the diaphragm 95 is to prevent any chattering or metallic ring being produced. The purpose of having the armature permanently magnetized is to increase the magnetic field, it being understood that in all of the embodiments of my 100 invention, herein shown, the diaphragm, as well as the armature, is resiliently suspended in the magnetic field. At any desired distance from the outer periphery of the diaphragm 104, I secure a split ring 110, between which the diaphragm extends, and this ring 110 may be of any desired material, 105 preferably resilient. 111 designates a re-

silent member surrounding the outer periphery of the diaphragm 104 and having its inner periphery split, in order that the edges will seat upon and engage the sides of the 5 split ring 110. The resilient ring 111 may be constructed of any desired material, such as for example, rubber or spring metal, and is seated in an annular groove 112 in the housing 100, it being seen that the receiver 10 cap 113 is in threaded engagement with the housing 100 and also bears against the resilient member 111. An insulating washer 114 is also preferably provided between the armature 102 and the diaphragm 104. The 15 resilient bumpers 103 preferably extend beyond the magnetic poles of their respective electro-magnet. It will of course be understood that the resilient member 111 may be split at its outer periphery or otherwise 20 formed, since my invention, in its broad and generic scope, provides means to resiliently suspend the diaphragm within the magnetic zone or field, and is not limited to any specific type of members such as 62 or 110 25 and 111.

It will now be apparent that I have devised a novel and useful construction of a telephone receiver, which embodies the features of advantage enumerated as desirable 30 in the statement of the invention and the above description; and while I have, in the present instance, shown and described a preferred embodiment thereof which will give in practice satisfactory and reliable results, 35 it is to be understood that the same is susceptible of modification in various particulars without departing from the spirit or scope of the invention or sacrificing any of its advantages.

40 Having thus described my invention, what I claim as new and desire to secure by Letters Patent, is:-

1. A telephone receiver, comprising a casing, electro-magnets within the casing, a 45 diaphragm, a sectional ring through which said diaphragm extends, a resilient ring

having its inner periphery split to receive the peripheral portion of the diaphragm and having its edges engaging the sectional ring, and an armature carried by said diaphragm. 50

2. A telephone receiver, comprising a casing, electro-magnets within the casing, a diaphragm, a sectional ring through which said diaphragm extends, a resilient ring 55 having its inner periphery split to receive the peripheral portion of the diaphragm and having its edges engaging the sectional ring, and an armature secured to and insulated from said diaphragm. 60

3. A telephone receiver, comprising a casing, electro-magnets within the casing, a diaphragm, a sectional ring through which said diaphragm extends, a resilient ring 65 having its inner periphery split to receive the peripheral portion of the diaphragm and having its edges engaging the sectional ring, and a permanently magnetized armature secured to said diaphragm.

4. A telephone receiver, comprising a casing, electro-magnets within the casing, a diaphragm, a sectional ring through which said diaphragm extends, a resilient ring having its inner periphery split to receive the peripheral portion of the diaphragm 75 and having its edges engaging the sectional ring, and an armature spaced from, carried by, and insulated from said diaphragm. 70

5. A telephone receiver, comprising a casing, electro-magnets within the casing, a diaphragm, a sectional ring through which said diaphragm extends, a resilient ring having its inner periphery split to receive the peripheral portion of the diaphragm and having its edges engaging the sectional 85 ring, and a permanently magnetized armature spaced from, carried by, and insulated from said diaphragm. 80
